(57) **CLAIM**

The ornamental design for an integrating sphere for light flux meter, as shown and described.

DESCRIPTION

FIG. 1 is a perspective view of an integrating sphere for light flux meter showing my new design;

FIG. 2 is a front view thereof showing a sphere being mounted concentrically on top of a cylindrical base;

FIG. 3 is a rear view thereof showing an annular flange being formed circumferentially around the sphere;

FIG. 4 is a left view thereof;

FIG. 5 is a right view thereof;

FIG. 6 is a top view thereof showing a disk with a light source inlet being formed through the top of the sphere and aligning concentrically with the base;

FIG. 7 is a bottom view thereof; and,

FIG. 8 is another left view thereof with a light flux meter shown in broken lines.

The portions of the Figures shown in broken lines are shown for illustrative purposes only and form no part of the claimed design.
